Primary Examiner — Sandra Snapp*Assistant Examiner* — Ieisha N Price(74) *Attorney, Agent, or Firm* — Middleton Reutlinger(57) **CLAIM**The ornamental design for an adapter, as shown and
described.

DESCRIPTION

FIG. 1 is a perspective view of an adapter;
FIG. 2 is a front view of the adapter of FIG. 1;
FIG. 3 is a rear view of the adapter of FIG. 1;
FIG. 4 is a right side of the adapter of FIG. 1;
FIG. 5 is a left side of the adapter of FIG. 1;
FIG. 6 is a top view of the adapter of FIG. 1; and,
FIG. 7 is a bottom view of the adapter of FIG. 1.
The broken lines in the drawings illustrate portions of the
adapter and form no part of the claimed design.
